UNITED STATES PATENT OFFICE.

WILLIAM H. WAMSGANS, OF PEORIA, ILLINOIS.

JOINT FOR ARTIFICIAL LIMBS.

Application filed July 26, 1922. Serial No. 577,533.

To all whom it may concern:

Be it known that I, WILLIAM H. WAMSGANS, a citizen of the United States, residing at Peoria, in the county of Peoria and State 5 of Illinois, have invented new and useful Improvements in Joints for Artificial Limbs; and I do hereby declare that the following is a full, clear, and exact description of the invention, which will enable others skilled in 10 the art to which it appertains to make and use the same.

This invention has reference to a joint for artificial limbs and particularly to an ankle joint therefor.

15 The object of the invention is to provide a form of joint construction that will be exceedingly rigid, of few parts, strong and durable, and so organized that there will be a minimum of wear and consequently a joint 20 of exceedingly long life.

Another object is to furnish a joint that will have no lost motion and therefore no undesirable looseness of action even after protracted use.

25 In the past, joint structures for artificial limbs have consisted of a considerable number of parts that after a short time become too easily loosened, due to wear, resulting in much annoyance to the user, and it is my 30 purpose to provide a very simple type of joint of few parts that due to their form and arrangement can be easily and quickly assembled, will be noiseless and that will have practically no wear even after very long 35 hard usage.

To the end that the invention may be readily understood I have provided the accompanying drawing wherein—

Figure 1 is a side elevation of my invention 40 much enlarged showing part broken away to show interior structures:

Figure 2 is an elevation of the same showing a part thereof in transverse section, and

Figure 3 is a side elevation of a portion of 45 a grooved body portion of the joint shown in the preceding figures.

Broadly considered, my joint comprises a main body or shaft portion 1 into which is threaded a pair of spaced pins 2 common to 50 joints of this type for carrying a leg portion, not shown, and a sleeve 3 enclosing the main body or shaft portion and located between the said pins, said sleeve having an extension or pin 4 for connection with the 55 usual foot portion, not shown.

The said main body or shaft portion 1 is

preferably of hardened steel and at substantially the middle of its length it is reduced in diameter, or grooved, to create a neck-portion 5 of less diameter, the groove receiving 60 into it a series of hardened rollers 6 as clearly illustrated in Figures 1 and 2.

Said rollers are of such diameter that they project beyond the cylindrical surface of the body 1 and when all are placed in the groove, 65 receive upon them, and are enclosed by the said sleeve 3, the bore of the latter being of such diameter only as to just slip over the rollers thus assembled, the assembly being clearly shown in Figure 2 wherein the portion 5 is shown in transverse section.

The shoulders at each side of the neck-portion 5 created by providing the groove prevent endwise movement of the rollers, no 70 further aid being required.

75 One of the pins 2 being in place the parts are assembled as described, whereupon by screwing the other pin into place the sleeve 3 is retained in position upon the roller, completing the assembly.

80 The groove is of considerable width and therefore the rollers can be of much length or nearly equal in extent thereto. And the extent of the groove and the length of said rollers can be substantially the distance between the pins 2 whatever that distance may be. The large extent of roller surface provided, and the fact that the bore of the sleeve 85 3 can be equal in measurement to the length of said rollers, extensive bearing surfaces 90 are provided with a minimum of wear.

The device is extremely rigid and strong because of the bearings provided, and no retaining means are required other than the pins 2 for the sleeve, said pins serving in 95 this capacity in addition to their principal office.

In order to lighten the structure excess weight may be removed by boring out the body portion 1 as shown.

100

I claim:

An ankle joint for artificial limbs comprising in combination a one piece shaft having intermediate its ends a peripheral groove, a series of rollers seated in said groove, the 105 shoulders forming the side walls of the groove retaining the rollers in position, a sleeve having a straight bore substantially equal in diameter to the combined reduced diameter of the shaft in said groove and the 110 seated rollers adapted when the latter are seated in said groove to be slipped over and

upon them, there being a stem extending from the sleeve for attachment to a part of an artificial limb, and a separate portion secured in the shaft at each side of the groove and the sleeve for holding the said sleeve in place upon the rollers and adapted for attachment to another part of the limb, one of the last named portions adapted to be at-

tached to the shaft after the rollers and sleeve have been assembled on said shaft.

In testimony whereof I affix my signature in presence of two witnesses.

WILLIAM H. WAMBSGANS.
